UNITED STATES PATENT OFFICE.

WALTER MACLEOD, OF FORT THOMAS, KENTUCKY, AND WILLIAM HEXT, OF CINCINNATI, OHIO.

SAND-BLAST DEVICE.

1,026,688.

Specification of Letters Patent. Patented May 21, 1912.

Application filed May 17, 1909. Serial No. 496,605.

To all whom it may concern:

Be it known that we, WALTER MACLEOD and WILLIAM HEXT, citizens of the United States of America, and residents of Fort 5 Thomas, county of Campbell, State of Kentucky, and Cincinnati, county of Hamilton, State of Ohio, respectively, have invented certain new and useful Improvements in Sand-Blast Devices, of which the following 10 is a specification.

Our invention relates to sand blast devices, wherein sand is taken up from a collector by suction created by compressed air, and is ejected by the compressed air against 15 the object which is to be sanded.

The object of our invention is a sand blast device wherein the sand, when taken up at the collector is kept together and is carried along through the hose, or conduit, in a 20 condensed stream, and is ejected from the nozzle in a central condensed jet, which is surrounded by a jacket of air, so as to prevent the nozzle's being cut by the sand.

Referring to the drawings, which form 25 part of this specification, Figure 1 is a side elevation of a sand blast device embodying our invention, the sand reservoir being shown upon a reduced scale, and the hose which connects the collector to the nozzle 30 being broken out, and the ends being brought together to economize space. Fig. 2 is a detail plan view of the collector. Fig. 3 is a sectional view thereof, taken upon line 3—3 of Fig. 2. Fig. 4 is a view 35 partly in elevation and partly in central vertical section of the nozzle.

Referring to the drawings: The sand reservoir, A, and its supporting frame, a, are of ordinary construction. The collector 40 consists of a pan, b, and a cover, b'. Pan, b, has a reduced neck, b², and around its periphery is surrounded by a flange, b³. The cover has likewise a reduced neck, to 45 register with the neck, b², of the pan, and is of the contour of the pan, with the exception that it has its front end cut away so as to leave an air slot, B, between it and the front edge of the pan. Cover, b', has an annular collar, b⁴, which is adapted to be secured by a set screw, a', to the discharge end, a², of the sand reservoir. Both the

cover, b', and the pan, b, have lateral lugs, b⁵, which receive bolts for securing the pan and the cover together.

At the delivery end of the device is a nozzle, D, which fits into an air chamber, E. In axial alinement with the nozzle, D, is a sand delivery pipe, F, which is connected by a hose, G, to a pipe, g, which is held by a thumb-screw, g', in the neck of the sand 60 collector. Below the sand pipe, F, chamber, E, has a collar, e, into which an air pipe, H, leads. The opening of the pipe, H, is controlled by a cock, h. The nozzle, D, is tapered at, d, and into the tapered portion 65 the sand pipe, F, projects, extending past the air port, e. The air chamber, E, is made of a shape such as to leave an air space between the pipe, F, and the walls of the chamber, E.

The operation of the device is as follows: Sand is deposited from the pipe, a², leading from the reservoir, A, centrally upon the bottom of the pan, b. When the cock, h, is opened, compressed air rushes into the air 70 chamber, E, and is ejected thence outward through the nozzle, D. This forcible exit of the air through the nozzle creates a vacuum in the sand pipe, F, and creates a suction through the hose, G, which draws the air in 75 through the slot, B, of the sand collector. By reason of the slot, B's, being of a width greater than the neck, b², of the sand collector, and of the curvature of the walls of the collector leading into the reduced exit, 80 the air surrounds the sand upon the center of the bottom of the pan in diametrical currents, as indicated by the arrows in Fig. 2, and carries the sand along the center of the pipe, G, so that the sand is ejected from the 85 sand-pipe, F, in a central jet, as indicated in Fig. 4. The compressed air from the pipe, H, is ejected from the air chamber, E, in the form of a jacket, which surrounds the jet of sand, and prevents the sand's cutting 90 the nozzle, D.

What we claim is:

1. In a sand blast device the combination of a sand collector consisting of a pan and a cover for the pan, both of which have a reduced delivery neck, the pan projecting beyond the front edge of the cover and

forming thereby an air inlet, the cover having an opening adapted to admit sand centrally to the bottom of the pan.

2. In a sand blast device, a sand collector, 5 consisting of a pan and a cover for the pan, the pan projecting beyond the front edge of the cover, and thereby forming an air inlet port, a sand delivery port, and a port pro-

vided in said cover between said air inlet and said sand delivery port for admitting 10 sand to said collector.
